(57) CLAIM

The ornamental design for a golf club head, as shown and described.

DESCRIPTION

FIG. 1 is a heel-side rear perspective view of a golf club head embodying the inventive design.

FIG. 2 is a toe-side rear perspective view thereof.

FIG. 3 is a rear elevational view thereof.

FIG. 4 is a top plan view thereof.

FIG. 5 is a toe-side elevational view thereof.

FIG. 6 is a heel-side elevational view thereof; and,

FIG. 7 is a front elevational view thereof.

The dash-dot chain lines immediately adjacent the shaded areas represent the bounds of the claimed design, while all other broken lines are directed to environment and are for illustrative purposes only; the dash-dot chain lines and other broken lines form no part of the claimed design.

1 Claim, 7 Drawing Sheets

FIG. 1

FIG. 2

FIG. 3

FIG. 4

FIG. 5

FIG. 6

FIG. 7
